MACHINE FOR THREADING CAN COVERS

John M. Hothersall, Brooklyn, N. Y., assignor to
American Can Company, New York, N. Y., a
corporation of New Jersey

Application February 20, 1931, Serial No. 517,241

21 Claims. (Cl. 153—72)

The present invention relates to machines for threading can covers or the like, and has particular reference to an improved form of a threading device utilizing interior and exterior threading elements.

The principal object of the present invention is the provision of a threading machine for operating upon can covers or similar articles by shaping a wall of the article between internal and external threading elements.

An important object of the invention is the provision of a threading head formed with internal and external threading elements which fit one within the other during a threading operation on a can cover.

An important object of the invention is the provision of a machine of the character described for accurately holding the article being threaded in proper position to prevent misalignment relative to the threading elements thus insuring accurate threading.

An important object of the invention is the provision of a machine for forming threads in circular articles, which is of simple and rigid construction, the threading elements during the threading operation engaging an unusually large surface of the article being threaded thus insuring more accurate threading.

Numerous other objects of the invention will be apparent as it is better understood from the following description, which, taken in connection with the accompanying drawings, discloses a preferred embodiment thereof.

Referring to the drawings:

Figure 1 is a plan view of a machine embodying the invention;

Fig. 2 is a transverse sectional view taken substantially along the broken line 2—2 in Fig. 1;

Figs. 3, 4 and 5 are enlarged fragmentary central sectional views taken through the threading head and illustrating a can cover and its threading elements in different positions, Fig. 3 showing them in threading position, and Figs. 4 and 5 showing the can cover in two different stages of feeding into the threading elements;

Fig. 6 is an end elevation of the upper part of the machine;

Fig. 7 is a sectional view of the can cover feed as viewed along the line 7—7 in Fig. 2; and

Fig. 8 is a perspective view of a typical can cover illustrating the results obtained in the threading machine.

The machine disclosed in the drawings as a preferred embodiment of the present invention is adapted to thread articles such as can cov-

ers, caps, nozzles, necks, etc., which are provided with cylindrical sections. Can covers of the screw neck type are selected to exemplify the steps of operation. These can covers are fed into the machine in processional order through a chute and the lowermost cover is removed from the chute by a sliding feed device which positions it into axial alignment with a holder mandrel.

The holder mandrel is mounted on one end of a constantly rotating shaft adapted to move longitudinally to insert the mandrel on the inside of the positioned can cover and to carry it into threading position. An exterior wall of a part of the mandrel is threaded and it is this threaded part which enters into the can cover, the diameter of the threaded part being less than the diameter of the can cover part. A spring-mounted pressure plate assists in holding the can cover during this mandrel insertion.

A chuck is mounted adjacent and substantially in line with the mandrel, being secured to a constantly rotating shaft rotatably mounted in a lever device which operates to shift the shaft and chuck bodily. This chuck is cup-shaped and provided with a pocket into which the cover and mandrel move, the diameter of the pocket being greater than the diameter of that part of the can cover to be threaded. An internal wall of the chuck is provided with threads, this constituting a threading die element. A spring-controlled knockout pad cooperates with the pressure plate to properly hold the can cover as it reaches its position within the chuck.

Rocking of the chuck shaft lever under cam action now takes place and moves the threaded part of the chuck into a position eccentric to the threaded part of the mandrel and clamps the wall of the can cover therebetween at a common point of tangency. The clamped cover rotates with the rotating chuck and mandrel and a thread is formed in the peripheral cover wall during this rotation.

The mandrel is then withdrawn from the chuck and the knockout pad and the pressure plate cooperate to strip the threaded cover from the chuck and from the mandrel whereupon it falls through a discharge opening and out of the machine.

Having more particular reference to the drawings it will be observed that can covers 16 move by gravity down an inclined chute 11 formed in a frame 12 and are maintained in a single line within the chute by side plates 13 (Figs. 1, 2 and 7). The frame 12 is slotted longitudinally of

the chute to form a passage 20 for an extended neck part 14 of the can cover. The frame 12 is an integral part of a bracket 15 bolted to a bed member 16 carried on the upper end of supporting legs 17.

The bracket 15 is transversely slotted at 19 and a feed slide 21 has sliding movement therein. The feed slide 21 is provided with a pocket 22 which engages, when in retracted position, the neck part 14 of the lowermost can cover 10 as it rests in the chute 11 (Fig. 2).

The slide 21 is moved within its slideway 19 and across the stack of covers in the chute, cutting out or separating the lowermost cover. To effect this movement a link 26 is pivoted at 27 to the slide 21 and pivotally connects at 28 to the end of an arm 29 mounted on a rock shaft 31. The shaft 31 is journaled in brackets 32 (Figs. 1 and 6) projecting outwardly from the bed 16. The shaft 31 also carries an arm 33 which is pivotally connected at 34 to an adjustable link 35 pivotally mounted on a crank pin 36 carried on a disc 37 secured to a longitudinal shaft 38 journaled in bearings 39 formed in the bed 16.

The shaft 38 carries a gear 41 which meshes with a pinion 42 secured to a drive shaft 43 journaled in bearings 44 formed in the side walls of the bed 16. Power is applied to rotate the shaft 43 in any suitable manner, as by means of a belt pulley 45 mounted on one end of the shaft. Rotation of the drive shaft, through the described connections, oscillates the shaft 31 and moves the slide 21 back and forth to effect removal of a can cover from the chute.

The lowermost can cover 10 during this movement is prevented from falling forward by an L-shaped plate 46 (Figs. 2 and 7) secured to the face of the frame 12. A slot 47 cut in the frame 12 and joining with but extending at right angles from the slot 20 provides the passageway for the neck 14 of the can cover. The can cover as thus brought into its forward position by the slide 21 and supported in the pocket 22 of the slide is between faces of the holding mandrel and the chuck.

One of the threading elements for the apparatus is carried on the holder mandrel which is mounted for operation above the bed member 16. This mandrel comprises a disc 51 from which a conical stem 52 projects, the stem terminating in a cylindrical head 53 of a diameter less than the diameter of the neck part 14 of the can cover 10 and this head is provided with exterior threading elements 54. The disc 51 is threadedly engaged on the inner end of a horizontal shaft 55 journaled for rotation and for sliding movement within bearings formed in brackets 56 projecting upwardly from the bed 16.

The mandrel disc 51 (Figs. 3, 4 and 5) carries a pressure plate 57 which is adapted to slide relative to the disc during certain movements of the mandrel. The pressure plate is mounted on the forward ends of spaced rods 58 which extend at their rear ends through spring barrels 59 threadedly secured in the disc 51. A coil spring 60 is positioned on each rod 58 and is partially confined within its spring barrel 59. Locknuts 61 threadedly secured on one end of each rod 58 beyond the end of its spring barrel 59 limit the forward movement of the rod and determine the forward position of the plate 57 as held by the springs 60.

The can cover 10 in its forward position with the slide 21, is in axial alignment with the shaft 55 and closely adjacent the end of the mandrel head 53 (Fig. 1) and the pressure plate 57 held at

that time by its springs 60 in forward position and away from the disc 51. The shaft 55 is then moved longitudinally and the mandrel head 53 enters the cover as will be hereinafter more fully explained. This longitudinal sliding of the shaft 55 is effected in the following manner.

A collar 62 (Figs. 1 and 6) is mounted on the shaft 55 and is provided with a peripheral groove 63 in which rollers 64 are located, these being rotatably carried on pins secured to opposite arms 10 of a yoke 65 mounted on a rock shaft 66 journaled in bearings formed in brackets 67 bolted to the bed 16. The rock shaft 66 also carries an arm 68 which is connected to one end of a spring 69 held at its opposite end on a pin 71 extending from the bed 16.

The arm 68 carries a cam roller 72 which rides on the cam surface of a face cam 73 carried on the shaft 38. The spring 69 holds the roller 72 in engagement with its cam 73 and shifting movement of the arm 68 by reason of the contour of the cam is transmitted through the rock shaft 66 and the yoke 65, thereby shifting the rollers 64, the collar 62 and the shaft 55 back and forth.

This collar and roller construction permits continual rotation of the shaft 55 throughout its longitudinal movement. Rotation of the shaft is effected by a gear 74 (Fig. 1) secured thereto which meshes with a gear 75 carried on a horizontal shaft 76 journaled in bearings formed in brackets 30 77 projecting upwardly from the bed 16. The shaft 76 also carries a gear 78 which meshes with the gear 42 on the drive shaft 43 (Fig. 2). The gear 42 is sufficiently wide to operate with both of the gears 78 and 41. The gear 75 has a sufficiently wide face, as illustrated in Fig. 1, to permit the full sliding movement of the shaft 55 while maintaining geared connection between the shafts 55 and 76 the gear 74 merely moving along the gear 75 at such time. 40

The threading chuck comprises a chuck head 81 (Figs. 1, 2 and 3) threadedly mounted on one end of a horizontal shaft 82 rotatably mounted in a sleeve 83 formed on the forward end of a duplex lever 84 which is mounted for oscillation on the shaft 76, between two of the bearings 77. An arm 85 of the lever 84 carries a pin 86 upon which is rotatably mounted a cam roller 87 which rides upon the periphery of a cam 88 secured to the shaft 38. The roller 87 is maintained in engagement with the cam 88 by a spring 91 interposed between a pin 92 projecting from the bed 16 and an extension 93 formed on the arm 85. The contour of the cam 88 thus determines the axial position of the chuck 81 through the controlled oscillation of the lever 84 on its pivot shaft 76. 50

Provision is made for constantly rotating the shaft 82 with the chuck 81 irrespective of its axial position and for this purpose the shaft carries a gear 95 which meshes with the gear 78. 60 The center of the gear 78 being the center of oscillation of the lever 84, the gears 78 and 95 remain in mesh at all times.

The chuck is provided with an interior pocket 101 which connects with a cylindrical chamber 102, the walls of which are provided with internal threads 103 which form a threading die (Figs. 3, 4 and 5). The head 53 and chamber 102 thus form male and female threading members.

The rear wall of the chuck 81 where it is joined to its shaft 82 is recessed at 106 to provide a pocket for a knockout pad 107 formed on the inner end of a knockout rod 108 which terminates in a reduced portion 109. The rod 108 and its extension 109 is located in and slides longitudinally of a 70 75

horizontal bore 111 extending along the center of the shaft 82. A spring 112 encircles the reduced portion 109 of the rod 108 and is confined between the junction wall of the rod 108 with its end 109 and a nut 113 threadedly secured in an opening 114 formed in the end of the shaft 82, this opening communicating with the bore 111. Lock-nuts 115 are threadedly secured in an adjusted position on the terminal end of the knockout rod.

10 Prior to the longitudinal feeding movement of the shaft 55 it is in axial alignment with the shaft 82 and the knockout pad 107 at such time, under the action of the spring 112, is forward of its recess 106, being within the open end of the pocket 101 of the chuck 81 and its forward face being substantially flush with the face of the chuck. This flush position of the pad is maintained by the locknuts 115 engaging the outer face of the nut 113 and limiting the action of the spring 112 on the rod 108. The pressure plate 57 at this time is in extended or forward position of the disc 51 as illustrated in Figs. 1 and 4.

The shaft 55 then moves forward and the pressure plate 57 engages the can cover 10, which is supported at the time on the slide 21, and moves the outer face of its neck part 14 into engagement with the face of the knockout pad 107. Continued movement brings the mandrel head 53 into the can cover, the springs 60 yielding to permit the relative movement between the pressure plate 57 and the disc 51 of the mandrel. The spring 112, holding the knockout pad 107 in its forward position, is stronger than the combined springs 60 and the cover is therefore held clamped between the knockout pad 107 and the pressure plate 57 during yielding of the springs 60. This initial entering of the mandrel head within the can cover is illustrated in Fig. 4. The slide 21 moves back out of the way as soon as the can cover is clamped between the plate 57 and the knockout pad 107.

The continued forward movement of the shaft 55 positions the mandrel head 53 fully within the neck part 14 of the can cover at which time the forward face of the mandrel head engages the wall of the can cover, the pressure plate 57 at such time reaching the position illustrated in Fig. 5 wherein it is in solid contact with the disc 51. Continued forward movement of the shaft 55 thereafter compresses the spring 112 and the knockout pad 107 is forced backwardly, the can cover at such time being moved farther into the pocket 101 of the chuck 81. This movement continues until the knockout pad 107 is fully seated in its recess 106 and the can cover has been moved to the position illustrated in Fig. 3, wherein its neck part 14 is fully within the chamber 102 and its outer flange is held between the face of the chuck 81 and the pressure plate 57. It is now in position for threading.

60 The lever 84 is then oscillated on its shaft 76 by the cam 88 and the center of the shaft 82 and chuck is brought into a position out of alignment or eccentric to the center of the shaft 55 and its mandrel. This clamps the wall of the cover neck part 14 between the threading elements 54 and 103, it being remembered that both mandrel and chuck are rotating constantly at the time. A common point of tangency thus obtains in the engaged part of the cover and the engaging sections of the threading elements and this tangency is maintained as the mandrel, cover and chuck rotate on their respective axes. A threaded surface 120 (Fig. 8) is thus formed on the neck 14 of the can cover 10.

70 The completely threaded can cover is now

ready for discharging from the threading head and the shaft 82 is shifted back into axial alignment with the shaft 55 which then moves back. The can cover held on the mandrel head 53 by the knockout pad 107 is thus carried out of the pocket 101 of the chuck 81, the pad 107 following the mandrel head under the action of its spring 112 and knocking out or stripping it from the chamber 102 until stopped by the nuts 115 striking against the outer wall of the nut 113.

During this movement the springs 60 of the pressure plate 57 are under compression and the pressure plate is against the disc 51, spring 112 being much stronger than the combined springs 60. In this manner the can cover clears the chuck 81 but is still held between the pad 107 and the pressure plate 57 while the disc 51 and the mandrel head 53 continue to move backward, the springs 60 thereupon expanding and retaining the pressure plate in cover clamping position against the pad 107.

The pressure plate 57 under the action of its expanding springs holds the can cover in this clamped position (Fig. 4) until the rods 58 have slid through the disc 51 and the nuts 61 strike 25 against the ends of the spring barrels 59 (Fig. 1). At such engagement the face of the plate 57 is then flush with the face of the mandrel head 53 and the final movement of the shaft 55 draws the plate 57 away from the can cover 10. The can cover, thus freed from both mandrel and chuck, falls through a discharge opening 121 in the bed 16 and into any suitable place such as a receptacle 122 (Fig. 2) placed to receive it.

By utilizing the exterior threading element 54 35 and the internal threading element 103 a greater surface of the can cover wall being threaded is engaged by the threading elements and the result is an easier and more accurate threading action. The threading element of the mandrel 40 being enclosed within the threading element of the chuck furthermore insures greater rigidity of the threading parts by one part supporting the other. The can cover being spring-held by the pressure plate against the face of the chuck 45 also aids in correct threading action and there is therefore not the tendency for the parts to be moved out of alignment.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a can cover threading machine, the combination of a holder mandrel adapted to engage the interior of a can cover for a threading operation, a chuck mounted adjacent said mandrel and having an inside surface formed as a threading die, means for moving the chuck bodily sidewise for pressing the cover against said threading die, and means for rotating said mandrel, cover and chuck while the cover is against said die to form threads in the cover.

2. In a can cover threading machine, the combination of a holder mandrel having threads 70 formed in its surface and adapted to engage the interior of a can cover for a threading operation, a chuck mounted adjacent said mandrel and having an inside surface formed as a threading die, and means for moving the chuck bodily side-

- wise for pressing the cover between said threading die and the threads formed on said mandrel to form threads in the cover.
3. In a can cover threading machine, the combination of a holder mandrel mounted on a mandrel shaft and having threads formed on its surface, a chuck mounted on a chuck shaft parallel to said mandrel shaft, said chuck having an inside surface formed as a threading die, means for imparting axial movement to said mandrel shaft to insert said mandrel into the cover and move the cover into said chuck, and means for bodily shifting said chuck shaft while maintaining parallelism with said mandrel shaft to move said chuck and press the cover between said threading die and the threads formed on said mandrel to form threads in the cover.
4. In a can cover threading machine, the combination of a holder mandrel mounted on a mandrel shaft and having threads formed on its surface, a chuck mounted on a chuck shaft parallel to said mandrel shaft, said chuck having an inside surface formed as a threading die, means for imparting axial movement to said mandrel shaft to insert said mandrel into the cover and move the cover into said chuck, means for bodily shifting said chuck shaft while maintaining parallelism with said mandrel shaft to move said chuck and press the cover between said threading die and the threads formed on said mandrel to form threads in the cover, and means for rotating said mandrel and said chuck during movements of their respective shafts and during the thread forming operation.
5. In a can cover threading machine, the combination of a holder mandrel adapted to engage the interior of a can cover for a threading operation, a chuck mounted adjacent said mandrel and having an inside surface formed as a threading die, means for moving said mandrel first into a positioned can cover and then with said cover into said chuck, and means for moving the chuck bodily sidewise for pressing the cover against said threading die to form threads in the cover.
6. In a can cover threading machine, the combination of a holder mandrel adapted to engage the interior of a can cover for a threading operation, a pressure plate carried by said mandrel, a chuck mounted adjacent said mandrel and having an inside surface formed as a threading die, and means for moving the chuck bodily sidewise for pressing the cover against said threading die while holding it against said pressure plate in position on said chuck to form threads in the cover.
7. In a can cover threading machine, the combination of a holder mandrel adapted to engage the interior of a can cover for a threading operation, feeding devices for positioning a cover in axial alignment with said mandrel, a chuck mounted adjacent said mandrel and having an inside surface formed as a threading die, means for moving said mandrel to engage the positioned cover and move it into said chuck, and means for moving the chuck bodily sidewise for pressing the cover against said threading die to form threads in the cover.
8. In a can cover threading machine, the combination of a holder mandrel adapted to engage the interior of a can cover for a threading operation, feeding devices for positioning a cover in axial alignment with said mandrel, a chuck mounted adjacent said mandrel and having an inside surface formed as a threading die, means

for moving said mandrel to engage the positioned cover and move it into said chuck and means for moving the chuck bodily sidewise for pressing the cover against said threading die while in said chuck, and means for rotating said mandrel, cover and chuck to cause said threading die to traverse the circumference of the cover wall to form threads therein.

9. In a can cover threading machine, the combination of a rotatable holder mandrel having external threads formed on its surface, a rotatable chuck having an inside surface formed with internal threads and adapted to extend around said mandrel, means for positioning a can cover on said mandrel and within said chuck, and means for positioning said mandrel and chuck eccentric to one another and clamping a wall of the cover between said external and internal threads of said rotating mandrel and chuck, and means for rotating the mandrel and chuck to form threads in said cover wall.

10. In a can cover threading machine, the combination of a rotatable holder mandrel having external threads formed on its surface, a rotatable chuck having an inside surface formed with internal threads and adapted to extend around said mandrel, means for positioning a can cover on said mandrel and within said chuck, means for positioning said mandrel and chuck eccentric to one another and clamping a wall of the cover between said external and internal threads of said rotating mandrel and chuck, and means for rotating the mandrel and chuck to form threads in said cover wall, and means for discharging the threaded cover from said chuck.

11. In a can cover threading machine, the combination of a rotatable holder mandrel having external threads formed on its surface, a rotatable chuck having an inside surface formed with internal threads, means for positioning a can cover on said mandrel and within said chuck, means for positioning said mandrel and chuck eccentric to one another and clamping a wall of the cover between said external and internal threads of said rotating mandrel and chuck to form threads in said cover wall, means for discharging the threaded cover from said chuck, and means for ejecting the cover from said mandrel.

12. In a can cover threading machine, the combination of a rotatable, cylindrical, holder mandrel having external threads formed on its periphery and of a diameter less than the diameter of a wall of the can cover to be threaded, a rotatable chuck formed with a cylindrical, inside, pocket section of a diameter greater than the diameter of the said can cover wall and having internal threads formed on its peripheral wall, and means for moving said chuck bodily sidewise for pressing the external and internal threads of said rotating mandrel and chuck toward one another and clamping the can cover therebetween at a common point of tangency and maintaining such engagement during rotation of the parts while forming threads in the can cover.

13. In a can cover threading machine, the combination of a holder mandrel, a chuck mounted adjacent thereto, means for feeding a can cover between said chuck and said mandrel, means for yieldingly supporting the can cover while moving it with said mandrel into said chuck, and threading elements carried by said chuck and said mandrel for forming threads in the can cover while in said chuck, and means

for moving one of said threaded parts bodily sidewise relative to the other.

14. In a can cover threading machine, the combination of a holder mandrel, a chuck mounted adjacent thereto, means for feeding a can cover between said chuck and said mandrel, means for yieldingly supporting the can cover while moving it with said mandrel into said chuck, means for rotating said mandrel, cover and chuck, and threading elements carried by said chuck and said mandrel for forming threads in the can cover while in said chuck, and means for moving one of said threaded parts bodily sidewise relative to the other.
15. In a can cover threading machine, the combination of a holder mandrel, a chuck mounted adjacent thereto, means for feeding a can cover between said chuck and said mandrel, means for yieldingly supporting the can cover while moving it with said mandrel into said chuck, threading elements carried by said chuck and said mandrel for forming threads in the can cover while in said chuck, and means associated with said yielding supporting means for discharging the threaded cover from said chuck.

16. In a can cover threading machine, the combination of male and female screw-threading members, means arranging said members in axial alignment and spaced relation for the reception of the cover, means for thereafter telescoping said members with the outer threading member enclosing the inner threading member and means for arranging them in relatively eccentric position to clamp said cover between the thread forming surfaces, and means for rotating said members.

17. In a can cover threading machine, the combination of a holder mandrel adapted to engage the interior of a can cover for a threading operation, a chuck mounted adjacent and adapted to extend around said mandrel and having an inside surface formed as a threading die, means for moving one of said parts sidewise relative to the

other, for pressing the cover against said threading die to form threads in the cover, and yielding clamping means operating at front and rear of the can cover between which the cover can slide edgewise while the mandrel is operating within the chuck and the chuck is operating on the outside of the cover.

18. In a can cover threading machine, the combination of an axially movable holder mandrel adapted to engage the interior of and support a can cover for a threading operation, a chuck mounted concentrically with said mandrel and having an inside surface formed as a threading die and means for moving one of said parts out of concentricity with the other, thereby pressing the cover against said threading die to form the threads in the cover.

19. In a can cover threading machine in combination, an inner threading member, a complementary outer threading member concentric with said inner member before the threading action proper, means for moving said members out of concentricity during the threading action proper and means for continuously revolving said members.

20. In a can cover threading machine, the combination of a holder mandrel adapted to engage the interior of a can cover for a threading operation, a complementary threading member mounted in axial alignment with said mandrel, and opposed yielding means adapted to engage a can cover in advance of said mandrel and member, one of said means also adapted to function as a knockout device.

21. In a can cover threading machine, the combination of male and female threading members mounted in axial alignment with each other, means for feeding a can cover to be threaded into axial alignment with said members and opposed yielding means adapted to cooperatively hold said can cover free of said members before and after the threading operation.

JOHN M. HOTHERSALL.
